EM 002205286-0001 * 3/2013
EM 007437249-0004 * 12/2019*Primary Examiner* — Paula Allen Greene(74) *Attorney, Agent, or Firm* — Sughrue Mion, PLLC(57) **CLAIM**

The ornamental design for a headphone, as shown and described.

DESCRIPTION

FIG. 1 is a perspective view of the front, top and right side of a headphone showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the headphone is included for the purpose of illustrating portions of the headphone and forms no part of the claimed design.
